UNITED STATES PATENT OFFICE.

JOHN S. PETER, OF ANGELICA, NEW YORK.

LUBRICATOR AND MEASURE.

SPECIFICATION forming part of Letters Patent No. 298,497, dated May 13, 1884.

Application filed January 19, 1884. (No model.)

To all whom it may concern:

Be it known that I, JOHN S. PETER, of Angelica, county of Allegany, New York, have invented a new and Improved Lubricator and Measure, of which the following is a full, clear, and exact description.

The principal object of my invention is to provide a lubricator of simple, inexpensive, and durable construction, and which shall automatically feed oil or other lubricant in measured quantities to the valves of locomotive-engines, when or after the steam is shut off by closing the throttle, a slightly-modified construction being applicable to the measurement of liquid or other substances.

The invention consists in an arrangement of a movable plate in the measuring-chamber, which latter connects by passages with the cup or reservoir or an outlet therefrom, said passages being suitably valved to control the flow to and discharge from the measuring-chamber.

The invention includes, also, special constructions and combinations of parts of the device, all as hereinafter fully described and claimed.

Reference is to be had to the accompanying drawings, forming part of this specification, in which similar letters of reference indicate corresponding parts in all the figures.

Figure 1 is a vertical sectional elevation of a lubricator embodying my improvements. Fig. 2 is a horizontal section on the line $x'x'$, Fig. 1; and Fig. 3 is a vertical sectional elevation of my invention in part, and as applied to a measure.

Referring first to Figs. 1 and 2 of the drawings, the letter a indicates the oil cup or reservoir of the lubricator, having any suitable removable plug, b , at the top, closing an aperture through which the oil may be filled into the cup. The cup a has an aperture at c in its bottom, preferably at the center, and a depending neck, d , which has or may have a separable bottom plate, e , fixed thereto, said plate e being centrally apertured at f , in line with aperture c and concentrically with the neck d . The apertures c and the neck d have interior screw-threads formed in them of like pitch to receive a screw-plug, which consists of a neck, g , entering aperture c , a screw-

plate, h , fitting the neck d , and a lower neck portion, i , which fits the threads of the aperture f of plate e , so that after the neck g and plate h have been screwed into place the plate e may be screwed onto the neck i and against the lower edge of the neck d , where said plate e is secured rigidly by screws or other means. The neck d forms the side walls of the oil-measuring chamber, the bottom of the cup a forms the top of the chamber, and the plate h its bottom or floor. In the neck g is fitted a double plug-valve, j , having upper and lower heads, k l , respectively, which seat themselves alternately at the top of neck g and at the bottom of the plate h . The valve-stem chamber or bore m of neck g has passages n , leading therefrom and from the interior of the cup a to the measuring-chamber o , the stem of the valve being shaped to allow free flow of the oil from cup a to the chamber o when valve l is closed and valve k open, and from the chamber o through the passages n and interior of neck i and the plug p , screwed or otherwise fitted into the neck i , and apertured at q , into the valve-chest r of the engine-cylinder. A vent-pipe, s , permits free flow of the oil from the measuring-chamber.

The operation is as follows: When the engine is taking steam, the steam-pressure through passage q will seat valve l and open valve k , and oil will flow from cup a into the chamber o ; and when the throttle-valve is closed and the steam is shut off, the valve k will close to cut off the flow from cup a , and the valve l will open and allow the oil that had previously entered the chamber o to escape to the steam-chest r , to lubricate the valves when they are moving over their seats while the engine is slowing down or stopping; hence the valves receive oil when they are not lubricated by the steam, and when effective lubrication is most needed.

It is evident that by screwing the cup a up or down the oil-chamber o may be enlarged or contracted at will, by the lowering or raising of the plate h relatively to the neck d ; hence the quantity of oil to be charged to the valves at a time may be accurately measured, and serious waste of oil prevented. By screwing the bottom of cup a down to plate h , all

flow of oil from the cup will be prevented. I make either valve *k* or *l*—preferably the valve *k*—adjustable along the valve-stem, and secure it by a jam-nut, *t*, or other device, so that the flow of oil from the cup *a* may be controlled by regulating the discharge through the valve *k*, as will be readily understood; or both valves may be adjustable on the stem, if desired.

10 In the modification shown in Fig. 3, the screw-neck *g* is fixed, by a pin or screw, *g'*, to the outlet *a'* from any liquid or other reservoir, as a tank, cask, or other vessel, and the plate *h* is fitted to the interior threads of the inverted cup *d'*, which is fitted to the threads of the neck *g*, and has any suitable upwardly closing vent-plug or valve or device at *u*, to insure discharge of the liquid from the measuring-chamber *o*, through the passages *n*, past the valve *l*, when open, and through neck *i'* into any vessel placed below to receive the liquid. In this case the nut *t* is applied at the lower valve, *l*, and the valves *k l*, instead of being lifted by steam-pressure, to allow the measuring-chamber *o* to fill, are lifted by a pivoted and weighted elbow-lever, *r*, which has a pin and slot or other suitable connection at *w* with the stem *j'* of the valve, said stem passing through a stuffing-box at *x* in the outlet *a'*. With the lever *r* in the position shown, the chamber *o* will be filled, and when the elbow-lever is swung over on its pivot toward the right hand the flow from *a'* will be cut off, and the measured liquid or substance in the chamber *o* will be discharged. The capacity of the lubricator or measure will vary with the diameter and length of the neck or cup *d* or *d'*.

I have shown the lubricator-cup *a* arranged directly over the neck *d* and plate *h*, as best suited for direct connection with the valve-chests of locomotive-engines; but the oil-cup

may be in the engine-cab and have an outlet, *a'*, connecting it with the measuring-chamber, as will readily be understood.

The details of construction may vary within the scope of my invention.

If desired, a graduated scale, *d²*, may be fixed to the under side of the plate *h*, to indicate the capacity of the measuring-chamber by a coincidence of the scale-marks with the lower edge of the cup *d'*, as shown in Fig. 3 of the drawings.

Having thus described my invention, I claim as new and desire to secure by Letters Patent—

1. The combination, with an oil-reservoir, of a measuring-chamber provided with an adjustable bottom having inlet and outlet passages, and valves for alternately closing and opening said passages, substantially as herein shown and described.

2. The combination, with the cup *a*, of the neck *d*, and the plug *g h i*, having passages *m n* to and from the cup and measuring-chamber *o*, respectively, and the valves *k l*, connected to be seated alternately, substantially as shown and described.

3. The combination, with the cup *a*, and parts *d g h*, forming the measuring-chamber *o*, of the valve *j*, having heads *k l*, adjustable on the valve-stem, to graduate the flow from the cup, substantially as shown and described.

4. The combination, with the cup *a*, neck *d*, plug *g h i*, having passages *m n*, and the valves *k l*, of the aperture-stem *p*, substantially as shown and described.

5. The combination, with the cup *d'* and outlet *a'*, of the stem and plate *g h*, apertured at *m n*, the connected valves *k l*, and the lever *r*, substantially as shown and described.

JOHN S. PETER.
